UNITED STATES PATENT OFFICE.

HARVEY L. BULLOCK, OF NORTH WHITE PLAINS, NEW YORK.

FUSE-BOX.

1,359,324.

Specification of Letters Patent. Patented Nov. 16, 1920.

Application filed July 25, 1919. Serial No. 313,133.

To all whom it may concern:

Be it known that I, HARVEY L. BULLOCK, a citizen of the United States, and a resident of North White Plains, in the county of 5 Westchester and State of New York, have invented new and useful Improvements in Fuse-Boxes, of which the following is a full, clear, and exact description.

The invention relates to magnetic blow-out fuse boxes using copper ribbon fuses, and its object is to provide certain new and useful improvements in such fuse boxes whereby the operator is enabled to quickly and conveniently renew a blown-out copper 15 ribbon fuse. Another object is to insure a positive contact between the ends of the ribbon fuse and the terminal blocks in the fuse box.

With these and other objects in view, the 20 invention consists of certain novel features of construction as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a side elevation of the im- 30 proved fuse box, parts being shown in section;

Fig. 2 is a side elevation of one of the terminal blocks;

Fig. 3 is a face view of the same;

Fig. 4 is a sectional side elevation of one 35 of the terminal wedges with its stem shown in elevation; and

Fig. 5 is a face view of the same.

In the upper corners of the box 10 are se- 40 cured the terminal blocks 11 and 12 engaged in the usual manner by the cable terminals. Each of the terminal blocks 11 and 12 is provided with oppositely disposed jaws 15 and 16 adapted to be engaged by a terminal 45 wedge 17 for clamping the corresponding end 18 of a copper ribbon fuse 19 between the jaw 16 and the wedge 17, as plainly shown in Fig. 1. The jaw 16 has an inclined face engaged by the corresponding in- 50 clined face of the wedge 17 to permit of securely clamping the end 18 of the ribbon 19 in place on drawing the wedge 17 in firm contact with the jaw 15 and the correspond- 55 ing end 18 of the ribbon 19.

In order to normally hold each terminal 60 wedge 17 in clamping position, the follow-

ing arrangement is made: Each terminal wedge 17 is provided with a stem 20 extending outwardly through the corresponding terminal block 11 or 12 and through an opening 21 formed in the corresponding side of the box 10. The outer end of the stem 20 has a bearing in a bracket 22 secured to an attaching plate 23 fastened to the outer face of the corresponding side of the box 10. 60 On the stem 20 is coiled a spring 25 extending within the opening 21 and seated at its inner end in a seat 26 formed on the corresponding terminal block 11 or 12. The outer end of the spring 25 presses against 70 a washer 27 held against a cotter pin 28 extending through the stem 20. By the arrangement described, the spring 25 exerts an outward pressure against the stem 20, thus holding the corresponding terminal 75 wedge 17 in clamping position.

In order to allow the operator to quickly release each terminal wedge 17, use is made of a hand lever 30 fulcrumed at 31 on the bracket 22 and having a cam end 32 adapted to engage the outer end of the corresponding stem 20. Normally the lever 30 hangs downward, as shown in Fig. 1, to allow the spring 25 to hold the corresponding terminal wedge 17 in clamping position, but 80 when it is desired to release the terminal wedge, it is only necessary for the operator to swing the lever 30 upward into the position shown in dotted lines in Fig. 1, whereby the cam end 32 pushes the stem 20 inward 85 and with it the terminal wedge 17 thus moving the latter out of clamping engagement with the jaw 15 and the corresponding end 18 of the ribbon fuse 19.

It is understood that in releasing the ribbon fuse 19, the operator simultaneously 90 swings the two levers 30 upward to simultaneously move two terminal wedges 17 out of engagement with both ends 18 of the ribbon fuse to release the latter, or, if 100 broken, to release the ends thereof.

It will be noticed that the stems 20 are under the tension of their springs 25 at the time the terminal blocks 17 are in released position, and as the levers 30 are now in 105 alignment with the stems 20 they are held in uppermost position thus permitting the operator to readily insert a new ribbon fuse 19. When this has been done, the operator swings both levers 30 downward to simultaneously 110 clamp the ends 18 of the ribbon fuse in position on the terminal blocks 11.

and 12 by the action of the terminal wedges 17. From the foregoing it will be seen that the operator is enabled to quickly and conveniently renew a blown-out or injured 5 copper ribbon. It will also be noticed that by the arrangement described a positive contact between the terminal blocks 11 and 12 and the ends of the ribbon fuse is produced.

Having thus described my invention, I 10 claim as new and desire to secure by Letters Patent:—

1. In a ribbon fuse box, a terminal block, a ribbon fuse, a terminal wedge coacting with the said terminal block to clamp one 15 end of the said ribbon fuse in place, and a spring-pressed means connected with the said wedge and exerting a pull on the wedge outwardly lengthwise of the ribbon to normally hold the wedge in clamping position.
2. In a ribbon fuse box, a terminal block, a ribbon fuse, a terminal wedge coacting with the said terminal block to clamp one 20 end of the said ribbon fuse in place, a spring-pressed means connected with the said wedge and exerting a pull on the wedge outwardly lengthwise of the ribbon to normally hold the wedge in clamping position, and manually controlled means adapted to engage the said spring-pressed means to 25 move the terminal wedge into release position.
3. In a ribbon fuse box, a terminal block, a ribbon fuse, a terminal wedge coacting with the said terminal block to clamp one 30

end of the said ribbon fuse in place, the 35 said wedge having a stem, and a manually controlled lever adapted to engage the said stem to move the said wedge into and out of clamping position relative to the terminal block. 40

4. In a ribbon fuse box, a ribbon fuse, a fixed terminal block having jaws, a terminal wedge fitting between the jaws to clamp one end of the said ribbon fuse in place between a jaw and the wedge, a spring- 45 pressed stem extending outwardly from the said terminal wedge and slidably mounted in the said terminal block, and a cam lever adapted to engage the outer end of the said stem to move the latter inward against the 50 tension of its spring to move the wedge out of clamping engagement with the terminal block.

5. In a ribbon fuse box, a ribbon fuse, a fixed terminal block having jaws, a terminal 55 wedge fitting between the jaws to clamp one end of the said ribbon fuse in place between a jaw and the wedge, a spring-pressed stem extending outwardly from the said terminal wedge and slidably mounted in the said terminal block, a bracket attached to the corresponding outer side of the box and forming a bearing for the outer end of the said stem, and a hand lever pivoted on the said bracket and having a cam end adapted to 60 engage the outer end of the said stem. 65

HARVEY L. BULLOCK.
